UNITED STATES PATENT OFFICE.

ORIN C. FENLASON, OF RAYMOND, WASHINGTON.

EGG AND FRUIT CARTON.

1,307,660.

Specification of Letters Patent. Patented June 24, 1919.

Application filed July 10, 1917. Serial No. 179,693.

To all whom it may concern:

Be it known that I, ORIN C. FENLASON, a citizen of the United States, residing at Raymond, in the county of Pacific and State 5 of Washington, have invented a new and useful Egg and Fruit Carton, of which the following is a specification.

This invention relates to egg cartons, and its primary object is to provide means, located within the cells, for cushioning the eggs, fruit, or other articles to be carried thereby, in a manner to prevent their breakage or damage during transportation.

Another object is to provide a cushioning 15 means adapted to yieldingly receive the articles placed in the individual cells and to exert sufficient pressure upon them to prevent any material lateral movement or the accidental displacement thereof, and having 20 means, when containing eggs, for facilitating the candling of the same, without the necessity of removing them from the carton.

The invention is designed as an improvement 25 on the subject-matter of my Patent No. 1,235,886, dated August 7, 1917, and is herein shown and described as applied to the identical structure of egg carton of said patent, though it should be understood, that 30 the cushioning device is equally applicable to any container provided with a plurality of rectangular cells for the reception of eggs, fruit, or other articles.

A full and complete understanding of the 35 invention may be obtained from a consideration of the following detailed description, taken in connection with the accompanying drawings forming a part of this specification; it being understood that while the 40 drawings show a practical form of the invention, the latter is not confined to strict conformity therewith, but may be changed or modified, so long as such changes or modifications mark no material departure from 45 the salient features of the invention, as specifically pointed out in the appended claims.

In the drawings, in which like reference characters designate like parts throughout the several figures:

50 Figure 1 is a plan view of the egg carton of my patent, having the improved cushioning means applied thereto.

Fig. 2 is a longitudinal sectional view thereof.

Fig. 3 is a cross sectional view of the same. 55

Fig. 4 is a detail perspective view of the preferred form of the device.

Fig. 5 is a perspective view of an egg carton showing one of the cushioning devices applied to a pair of cells. 60

Fig. 6 is a detail perspective view of another form of the invention, wherein a continuous cushioning device is shown, adapted to six cells of a carton.

Fig. 7 is a detail perspective view of an 65 individual cushioning member adapted to fit within a single cell of an egg carton or other carrier.

Since the exact structure of the egg carton proper forms no part of the present application, the improved cushioning means being, as has been stated, applicable to any egg carton or other similar container having a plurality of rectangular pockets or cells, no specific description of the same will be 75 made herein.

Referring to the drawings, there is shown, in Fig. 1, a container or cell case A provided with a plurality of cells B, each intended to receive an egg or other article, and to support the same in separated relation to each other. The cells B are preferably formed of longitudinal side walls, a longitudinal central partition strip, end walls and spaced 80 intermediate transverse walls or partitions defining cells, approximately square in plan view. These several parts may be formed in any desired manner and are preferably composed of strips of wood veneer, it having been found that the same may be kept in 85 cold storage without any deleterious effects therefrom, such as is found to be the case where it is attempted to store eggs in pasteboard or paper receptacles. 90

Ordinarily, these cells are of ample dimensions to receive the maximum size eggs, and when the cells contain such eggs, loss is sustained by reason of the close contact of the same with the walls of the cells, when jarred or jolted in transportation, the blow 95 being imparted from one egg to another through the partition walls. When, on the other hand, the eggs of the minimum size are carried in the cell case, breakage results from the freedom of movement allowed 100 within the cell when the egg is at liberty to move or roll around and strike the several adjacent walls thereof. 105

To overcome these defects, I have devised the herein described cushioning means, which is designed to fit within the cells of the case A and to yieldingly receive the 5 eggs, of different sizes, and to support them in spaced relation to the bottom and to the sides of the cell.

To this end, an oblong strip of wood veneer is utilized, of a width slightly less than the width of the cells B, and in the preferred form of the invention, as illustrated in detail in Fig. 4 of the drawings, the strip 1 is transversely scored at a central point, as indicated at 2, and bent to 15 form downwardly extending inclined walls 3, which are adapted to extend into the cells B and to coact with similar opposed walls 4 in supporting and cushioning an egg, in a manner to be explained.

20 The veneer strip 1 is suitably scored at 5 on the opposite side thereof at proper intervals to provide a pair of integral bottom members 6 of a width considerably less than the width of the cells B. A centrally located 25 aperture 7 is provided in each of the bottom members 6 for a purpose to be described. Cushioning means for two cells is thus provided, which may be formed from a single strip of wood veneer, and necessitates only 30 one score on the reverse side thereof and one reverse bend, in order to form the same, the other scores and bends being on the other side and in one direction, respectively, and this form is deemed the easiest to manufacture, the most easily handled, and consequently the most practical, since strips of wood veneer of comparatively short lengths, which otherwise might be wasted, may be utilized. The scoring of the veneer strip 40 provides a flexible or hinged connection between the walls 3 and 4.

In applying the cushioning device to a cell case, it is only necessary, as illustrated in Figs. 1 and 2, to introduce the bottom 45 members 6 into a pair of adjacent cells B either longitudinally or transversely of the cell case, when the connecting portion of the veneer strip underlying the score 2 will rest upon one of the transverse partition strips 50 or the central longitudinal strip, and will serve to support the cushioning means in two adjacent cells, the spring of the downwardly extending inclined cushioning walls 3 serving to maintain the bottom members 6 55 in a central position within the cells B, and somewhat above the bottom of the carton, with the opposed walls 4 in oppositely inclined relation to the walls 3, and having their upper edges bearing against the next 60 adjacent transverse partition of the cell case or the side walls of the same, as the case may be. By reason of the difference in the width of the bottom members 6 and the width of the cells B considerable outward movement 65 of the walls 3 and 4 of the cushioning means

may take place without contact between said walls and the said transverse partitions. Thus, an egg, indicated in dotted lines at C, and which may be taken as indicative of any minimum sized egg, will be supported with 70 in the cushioning means in a central position and spaced away from the transverse partitions by reason of the spring of the wood veneer composing the strip 1.

As shown in Fig. 2 of the drawings, the 75 point of the egg is adapted to enter and be supported in the aperture 7, in spaced relation to the bottom of the several strips composing the cell case A, and thus any danger of contact of the eggs with a table or other 80 support, or with other cartons, when in storage, is obviated. It will further be seen that by reason of the frictional contact of the walls 3 and 4 with the egg, the latter is prevented from accidental displacement 85 through the open end of the cell B. The free upper ends of the outer walls 4 are frictionally held against the adjacent transverse strips by reason of the egg itself.

Another form of the device is illustrated 90 in Fig. 6, in which a series of six cushioning members are formed from one continuous strip 8 of wood veneer similar to the herein-before described strip 1, being, however, approximately three times the length of the 95 same. In this form, it is necessary to make five scores on the reverse side of said strip and consequently five reverse bends, the members of the individual cushioning devices being formed as in the first described 100 form of the invention. Only two of the latter form of multiple cushioning devices are necessary when used in a cell case, having one dozen cells, which is the most practical 105 form of cell case. They are placed longitudinally in the cell case A and parallel to each other, with the several joining portions adjacent to the scores 2 resting upon the upper edges of the several transverse partitions, and the outer walls or members 4 resting 110 against and frictionally engaging the end walls of the cell case A in the same manner as the first-mentioned form of the invention. By reason of the extreme length of the last described form of the invention, it 115 has been found that the two-cell form of cushion is more easily assembled and the most practical. Upon reference to Fig. 2 of the drawing, it will be noted that the bend 2 extends above the partitions of the cell case 120 and may be grasped by the fingers in removing the cushioning strip from the cell case.

A further modification is illustrated in Fig. 7, of the drawings, wherein a single cell cushioning device is shown having a bottom member 9 provided with an aperture 10, and scored and bent to form upwardly extending diverging walls 11, which, when the device is introduced into a cell B, are adapted 125 to frictionally engage the adjacent walls of 130

said cell and to support the same, together with its contents, in proper position within the said cell.

When the several cells have been supplied 5 with eggs, as illustrated in Fig. 2, the same are safely supported by the cushioning means in spaced relation to the top and bottom of the said cell, and are prevented from contacting with said transverse partitions, 10 and the entire cell case or carton A may be then incased in a veneer wrapping, as shown and described in the hereinbefore mentioned application, or it may be wrapped in paper in the ordinary manner.

15 It will be seen that the apertures, formed in the bottom members of the several cushioning devices, form, in addition to a steady-ing means for the egg, a passageway for the rays of a suitable light when it is desired to 20 candle the eggs in the carton, it being only necessary to pass the loaded carton before said light without the necessity of remov-ing the eggs from the carton.

From the foregoing, it will be seen that 25 means have been devised for reducing the breakage of eggs to a minimum, while contained in cartons for shipping or storage, and that the said cushioning means may be manufactured from the same material as the 30 cell case or carton with a small number of scores and bends, thus reducing to a minimum the cost of manufacturing the same.

What is claimed is:—

1. The combination with a cell case, of a 35 cushioning device formed of a strip of veneer comprising a flat egg supporting bottom member of less area than the area of one of the egg cells and located within the same, said bottom member having an aperture for 40 the egg, upwardly-diverging imperforate side walls integrally and flexibly connected to and rising from the bottom member and adapted to bear against and frictionally engage the adjacent side walls of the cell at the 45 top to hold the said bottom member above the bottom of the cell case and maintain the side walls in spaced relation to the side walls of the cell, except at the top, whereby a cushioned double wall is provided on each side of 50 the egg.

2. A cushioning strip for ready insertion in cell cases, said strip being formed from an oblong blank of veneer having a pair of transverse score lines and bent on the score 55 lines to provide a flat bottom member and flat imperforate inclined side walls rising therefrom, said bottom member having a central aperture.

3. The combination with a cell case having 60 a plurality of cells, of a cushioning device therefor comprising a strip of veneer of a width less than the width of the cells of said cell case, said strip being scored at opposite sides at proper intervals and bent to form a 65 plurality of egg supporting bottom members

each of less width than the area of the cells, and each having a central aperture for the egg, and upwardly and outwardly flared imperforate side walls flexibly connected at one end to the opposite sides of the egg support-ing bottoms, certain of the side walls being flexibly connected together at their adjacent ends and adapted to rest upon the upper edges of the cell case to support the side walls in spaced relation to said cell case except at the top and maintain the bottom wall above the bottom of the case, the connected portions of the side walls extending above the upper edges of the cell case so that they may be grasped in removing the cushioning device therefrom.

4. The combination with a cell case, of a cushioning device made of a separate piece and applied thereto after the formation of the carton, said device consisting of a strip 85 of veneer scored at intervals, with a score at one side of the strip between every two scores at the opposite side, so that the strip may be bent in opposite directions to provide a series of bottom members of a width less than the width of the cells, a pair of connected inclined intermediate walls between each pair of bottom members, and an end wall at each end of the strip, the upright intermediate walls being hung at the score 90 line from the top edges of the cells with said walls spaced from the walls of the latter except at their upper portions, the end walls also bearing at their upper edges against the walls of the cell case and maintained in 95 spaced relation thereto.

5. The combination with a cell case, of a cushioning device therefor consisting of a strip of veneer scored transversely, with a score at one side of the strip between every 100 two scores at the opposite side, so that the strip may be bent in opposite directions to provide a series of bottom members, a series of inclined intermediate walls connecting the bottom members and being in turn flexibly 105 connected at the score line, and end walls at each end of the strip, said device being inserted in the top of the cell case with the connected intermediate walls hung from the upper edges of the cells, and said intermediate and end walls spaced from the walls of the cells except at their upper portions.

6. The combination with a cell case having longitudinal and transverse partitions defining a plurality of cells, of a cushioning de- 110 vice therefor comprising a strip of veneer scored at intervals at one side to bend in one direction and having its other side scored to bend in the opposite direction, the scoring being arranged so that a single score line of 115 one side is disposed between two score lines of the opposite side, the said two score lines defining an egg-supporting bottom member with a pair of inclined side walls, and the single score line providing a hinged connec- 120 125 130

tion between adjacent side walls, which hinged connection straddles one of said transverse partitions and extends above the same in position to be grasped by the hand 5 in removing the cushioning device therefrom.

In testimony that I claim the foregoing as

my own, I have hereto affixed my signature in the presence of two witnesses.

ORIN C. FENLASON.
